UNITED STATES PATENT OFFICE

JOHN A. WEITZ, JR., OF ENDICOTT, WASHINGTON

BRACKET FOR ELECTRIC LIGHTS AND FLASH LIGHTS

Application filed May 9, 1929. Serial No. 361,756.

This invention relates to a light bracket and more particularly to a device of this character which may be applied to a bed post or similar support and carry an electric light 5 to serve as illuminating means for a book or article being worked upon.

One object of the invention is to so form the bracket that a clamp which carries an electric light, such as a spotlight, may be 10 moved in a circular path and also angularly adjusted and thereby allow its light to be projected directly upon a book or other article so that it will be well illuminated without a person's eyes being injured by a glaring 15 light.

Another object of the invention is to provide a bracket of this character formed principally of sheet metal and thereby produce a bracket which will be simple and cheap in its 20 construction and at the same time strong and durable.

Another object of the invention is to so form a ring constituting part of the bracket that a lamp holder carried thereby may be 25 easily moved about the ring or hoop and retained in a set position by frictional engagement with the ring.

The invention is illustrated in the accompanying drawing, wherein.

Figure 1 is a perspective view of the improved light holding bracket, and

Fig. 2 is a longitudinal sectional view through the same.

This improved bracket includes a hoop or 25 ring 1 which may be referred to as a body, a support-engaging clamp 2 and a light-engaging clamp 3 connected with the body 1 by a clip 4. The hoop or ring 1 is formed of resilient sheet metal and for a portion of 30 its circumference is formed with a slot 5 dividing the body into upper and lower strips 6 and 7 spaced from each other by the slot. The clamp 2 which is adapted to be engaged 35 with a support, such as a bed post 8, is also formed of sheet metal and consists of a strip of metal bent intermediate its length to form jaws 9 joined at their inner ends by a bridge 10. The bridge is secured to the body or hoop 1 by a rivet 11 passed through the hoop 40 and bridge, as shown clearly in Fig. 2, and,

therefore, the clamp 2 will be permanently secured to the ring or hoop but the ring and clamp allowed to be turned relative to each other about the rivet. A bolt 12 is passed transversely through the arms 9 and carries 45 a winged nut 13 so that the arms which are normally spaced from each other may be drawn into tight gripping engagement about the bed post or other support 8. It will thus be seen that the bracket may be secured to 50 the bed post at any desired height and also moved about the bed post if found necessary.

The lamp holder or clamp 3 is similar in construction to the clamp 2 and consists of a strip of resilient metal bent intermediate its 55 length to form jaws 14 joined by a bridge 15 at their inner ends. A bolt 16 passes through the jaws 14 and carries a winged nut 17 so that by tightening the nut the jaws may be 60 firmly engaged about an electric light, such 70 as the flashlight 18. A rivet 19 connects the bridge portion of the clamp 3 with the clip 4 and, therefore, the clamp 3 may be turned about the rivet 19 in order to angularly adjust this clamp and cause light from the lamp 75 18 to be projected in a desired direction. The clip 4 extends transversely across the spaced strips 6 and 7 and consists of a strip of metal having its end portions bent to form arms 20 which engage against the inner faces of these 80 strips. Therefore, the clip will straddle the strips 6 and 7 and slidably mount the clip upon the hoop or ring. It should be noted 85 that the dimensions of the clip are such that when it is applied to the ring the strips 6 and 7 will be drawn toward each other. These strips have a tendency to return to their normal spaced relation and, therefore, a binding action will take place between the clip and the ring or hoop and cause the clip 90 to be frictionally held in a set position upon the ring.

When the bracket is in use, the clamp 2 is engaged about a bed post or like support and firmly secured by tightening the nut 13. If 95 it is found that the bracket does not project from the post in the desired direction, it is merely necessary to loosen the nut 13 sufficiently to allow the clamp to be turned about the post and when the nut is again tightened 100

the clamp will be firmly held in a set position. By moving the clip 4 about the ring the bracket 3 may be swung to a desired position and by tilting the ring and clamp 3 5 about the rivets 11 and 19 the electric light may be set at such an incline that its light will be projected upon a book or other article in front of a person and cause it to be well illuminated without light shining into 10 a person's eyes. I have, therefore, provided a bracket for supporting an electric light which will be efficient in operation and may be easily applied to a bed post and adjusted.

Having thus described the invention, I 15 claim:

1. A lamp support comprising a hoop formed with a circumferentially extending slot dividing the same into spaced strips, a clamp pivoted to said hoop at the opposite 20 side thereof from its slot and adapted to grip a support, a clip slidable upon said hoop in straddling relation thereto and drawing the strips towards each other to effect binding between the clip and strips and retain the 25 clip in a set position upon said hoop, and a clamp pivoted to said clip and adapted to be secured about a light.

2. A lamp support comprising a body 30 formed of resilient material and slotted to provide spaced strips movable towards and away from each other, a mounting rotatably connected with said body and extending transversely from the body and adapted to be secured to a support, a clip slidable upon 35 the slotted portion of said body with the strips drawn towards each other and exerting frictional binding against the clip to retain the clip in a set position, and a lamp holder rotatably connected with said clip 40 and extending transversely from the body whereby the holder may be tilted to support a lamp at a desired angle.

3. A lamp support comprising a body having an arcuate portion slotted longitudinally 45 to form spaced strips, a mounting pivoted to said body and extending therefrom for engagement with a support, a clip slidable longitudinally of the slotted portion of said body and engaged with the strips to draw 50 the strips towards each other and create binding action between the clip and strips to frictionally retain the clip in a set position upon the body, and a lamp holder pivoted to said clip and projecting therefrom transversely 55 of the body.

4. A lamp support comprising a body, a mounting projecting from said body for engagement with a support, said body and mounting being pivotally connected where- 60 by the body may be tilted to a desired angle after the mounting is secured to a support, and a lamp holder projecting from said body and being slidably and pivotally connected therewith whereby the lamp holder may be 65 moved to an adjusted position upon the body

and tilted to a desired angle relative to the body.

5. A lamp support comprising a body having an arcuate portion slotted longitudinally to form spaced strips, a clamp carried by 70 said body for engagement with a support, a clip slidable longitudinally of the arcuate portion of said body and having flanges engaged about the strips to draw the strips toward each other and effect frictional binding 75 between the clip and strips, and a lamp-holding clamp carried by said clip, one of said clamps being pivotally mounted.

In testimony whereof I affix my signature.
